UNITED STATES PATENT OFFICE.

AUGUST KADOW, OF TOLEDO, OHIO, ASSIGNOR TO THE WESTLAKE MACHINE COMPANY, OF TOLEDO, OHIO, A CORPORATION OF OHIO.

CUT-OFF MECHANISM FOR GLASS-FORMING APPARATUS.

1,208,791.

Specification of Letters Patent. Patented Dec. 19, 1916.

Application filed September 11, 1912. Serial No. 719,866.

To all whom it may concern:

Be it known that I, AUGUST KADOW, a citizen of the United States, residing at Toledo, in the county of Lucas and State of Ohio, have invented certain new and useful Improvements in Cut-Off Mechanism for Glass-Forming Apparatus, of which the following is a specification.

My invention relates to apparatus for gathering glass, and the invention has for its object to provide a new and improved mechanism for cutting off the surplus glass from the gather while the same is in plastic condition.

15 The invention has for a specific object to improve upon the cut-off mechanism shown and described in my pending application, Serial No. 570,621, filed July 6, 1910.

The improvement consists in providing a 20 cam movement for actuating the cut-off knife which will operate more accurately and certainly than the mechanism disclosed in said application; in giving the knife an adjustability to compensate for wear; in 25 providing a knife which will give the glass a shearing cut, and in providing an arrangement of the knife and its actuating mechanism by means of which the surplus metal is thrown outwardly away from the furnace 30 instead of inwardly toward the furnace as in the original machine.

In the machine described in the application just referred to a ram or movable gathering mechanism is provided which enters 35 the working opening of the furnace and makes the gather through a ring of refractory material which floats on the surface of the metal. In this machine the cut-off knife is pivoted to the ram and cuts off the 40 surplus metal from the gathering mold during the movement of the ram backward out of the working opening. The active stroke of this knife was toward the furnace. As a result it sometimes happened that the 45 surplus glass cut off, which, of course, was partially cooled and solidified by the gathering operation, was thrown far enough back into the furnace to enter the ring from which succeeding gathers were made. This was 50 very objectionable because it resulted in making the glass gathered lumpy and uneven. In the improved apparatus constituting my present invention the active stroke of the knife is in the opposite direction so

that there is no possibility of any glass severed from the mold being thrown back into the ring. Furthermore, the operation of the cut-off mechanism as originally constructed tended to lift the ram or gathering device to which it was attached causing a leak between the registering ports of the ram and its support. The apparatus of the present invention is so constructed as to prevent this.

While the novel construction and combinations herein described have particular utility when forming a part of a machine such as that shown in my pending application above referred to, they nevertheless might be employed to advantage in machines quite different in their general design and construction.

The invention is illustrated, in a preferred embodiment, in the accompanying drawing, wherein—

Figure 1 is a side elevation of a glass gathering apparatus provided with my improved cut-off mechanism, Fig. 2, a detail sectional view taken on line 2—2 of Fig. 1, looking in the direction of the arrows; Fig. 3, a detail plan view of the end of the ram showing the cut-off knife; Fig. 4, a side elevation of a cut-off knife; Fig. 5, a sectional view taken on line 5—5 of Fig. 4, looking in the direction of the arrows; Fig. 6, a detail view showing the preferred construction of what may be termed the operating rod of the knife, and Fig. 7, a view, in perspective, of the blade of the cut-off knife.

Like characters of reference designate like parts in the several figures of the drawing.

The cut-off mechanism of my present invention is shown as forming a part of a glass working machine like that disclosed in my pending application Serial No. 570,621 referred to above but only such parts of the machine are shown in the drawing herein as are necessary to make the purpose, function and operation of the improved cut-off mechanism understood.

Referring to the drawings, 10 designates a fixed drum and 11 a support or spider which is caused, by suitable mechanism, to rotate around the drum. On the spider is a carriage 12 which is capable of a limited circular movement with respect to the carriage for reasons which need not be specified as they do not concern the present invention. Fixed to the carriage 12 is a housing

13 through which slides a movable element 14 termed the ram. The ram carries at its lower or outer extremity a gathering mold consisting of an upper fixed mold element 15 and a lower swinging mold element 16 having a port 17 through which the gather is drawn up by suction. The lower mold element 16 is swung on its pivot into the open position shown in the full lines in 10 Fig. 1 after the gather has been made and the ram withdrawn from the furnace. The blank is then discharged into a spindle or blow pipe 18 for further treatment; the machine in question being designed particularly for the manufacture of incandescent light bulbs. The particular construction of the mold, and of the spindle and the mechanism employed for opening and closing the mold, do not concern the present invention 15 and therefore will not be described further.

The furnace is designated 19, its working opening 20, and the refractory ring which floats on the surface of the metal, 21. The ram is moved in and out of the working 25 opening of the furnace by any suitable mechanism. The drawing shows, in part, the mechanism shown in my previous application. A rack 22 is provided on the upper side of the ram which is meshed by a pinion 30 23 on a shaft 24 mounted in the housing 13. In rigid relation with pinion 23 is a smaller pinion 25 which is meshed by a rack 26 on a slide 27. Movements back and forth are imparted to the slide 27 through mechanism 35 (not shown).

The purpose of the cut-off mechanism forming the subject matter of this application is to remove from the bottom of the blank any surplus metal that may adhere thereto, that is, to cut off the gather flush with the bottom of the mold. The cut-off 40 preferably takes place while the ram is approximately midway between the point of gather and its innermost point at which the blank is delivered to the spindle. The dotted line representation of the mold and 45 cut-off mechanism of Fig. 1 illustrates the point at which the cut is made. The metal, under normal conditions, will fall back into the working opening. If, however, the cut 50 is jerky, which will be the case should the metal be too cold or should the knife meet with some obstruction such as a hard lump or stone, the glass, instead of being thrown 55 back into the ring, as sometimes happened with the machine as originally constructed, is simply thrown out of the working opening which does no harm.

The cut-off mechanism is constructed as 60 follows: 28 is a blade bolted to the L-shaped shank 29 formed with a slot 30 and secured to the pivoted arm 31 by means of the set screw 32 which passes through the slot 30. The pivoted arm 31 is formed with a lug 65 33 through which extends the adjusting

screw 34 which is held in place by the collars 35 and which engages a threaded opening 36 in the top of the shank 29. This arrangement gives adjustability for the purpose of taking up wear. The upper surface 70 of the blade 28 is concaved and its forward or cutting edge 37 is oblique to the line of movement of the knife so that the knife gives a shearing cut. The knife swings on a pivot 38 extending through the end of 75 the ram 14 and through the arm 31, the latter being secured to the pivot by a pin 38a. The knife is swung back and forth on its pivot by means of an operating rod on the ram which is reciprocated by engagement 80 with a stationary cam. The operating rod preferably consists of two members 39 and 40, the former extending into a socket 41 secured to the latter. The rod 39 carries at its inner end the transverse pin 42, the 85 ends of which project into slots 43 in the socket 41. 44 is a tension spring secured to the socket 41 and to a collar 45 on the rod 39. Pivoted to the upper end of the ram is a bell crank 46, one arm of which carries a roller 47 which extends into the box cam 48 rigidly connected with the carriage 12. As the roller 47 travels in a box cam instead of on top of an inclined surface as in the old machine there is no tendency for the 95 cut-off mechanism to raise the ram and cause a leakage between the registering air ports in the ram and its supports. The upper cam surface of the box cam holds the ram down upon the surface of the carriage on 100 which it slides. The lower cam surface keeps the knife from vibrating as it otherwise would. In describing the cam 48 as stationary it will be understood that the term is used in a relative sense, that is, relative to the longitudinal or radial movement of the ram. In the embodiment of the invention shown all of the apparatuses described are mounted upon the spider 11 which is revoluble. The other arm of the 110 bell crank 46 is connected by means of the coupling member 49 to the rod 40. The rod 39 is formed on its lower end with the eyelet 50 through which extends the pin 51 coupling the rod to the pivoted knife arm 52. 115

The operation of the cut-off mechanism above described is as follows: As the ram is withdrawn from the furnace, the roller 47 begins to run down the inclined portion 53 of the cam 48, it being understood that when 120 the ram is in position to make the gather the roller 47 is at the outer end of the cam 48, that is, in the position opposite to that shown in Fig. 1. The movement of the roller 47 through the inclined portion 53 of 125 the cam slot causes the bell crank to rock toward the drum 10 which pulls on the operating rod 40, 39 and draws the knife across the mold cutting off whatever surplus glass there may be at the inlet port of 130

the mold. The further movement inward of the ram brings the roller 47 into the portion of the cam slot designated 54 which has an opposite inclination and by this means 5 the knife is returned to its normal position. It will be understood that these same movements take place in reverse order when the ram is moved down to its gathering position. These movements of the knife are, 10 of course, idle movements.

The operating rod has the telescopic construction shown so that the knife and its actuating mechanism will not be injured in case the knife encounters some hard substance 15 in the glass. The sections of the rod are simply linked together by the spring 44. The spring is stiff enough so that if the glass is of normal consistency it will not stretch. If the knife meets with any considerable obstacle the spring 44 will yield. 20 When the knife wears it may be drawn toward the mold by loosening screw 32 and turning screw 34.

While I have described my invention in 25 a preferred embodiment, it will be readily understood that modifications might be devised without departure from the invention. Therefore I do not limit the invention to the particulars described and claimed except so far as they are made specifically 30 limitations in certain of the claims herein.

I claim:

1. In apparatus for gathering glass, the combination with a ram, a gathering mold 35 on the ram, a cut-off device pivoted to the ram, an operating rod secured to the cut-off device, a fixed cam, and a bell crank pivoted to the ram, one arm of which engages the cam, the operating rod being secured 40 to the other arm, said operating rod comprising two telescopic members, and a spring connecting said members.

2. In apparatus for gathering glass, the combination with containing means for a 45 supply of molten glass, of gathering mechanism adapted to enter and be withdrawn from said containing means and provided with an intake port, a cut-off knife standing normally away from the said port across 50 said intake port from side to side, and means for moving said knife so as to make the cut in a direction away from said containing means and immediately return the knife to normal position.

3. In apparatus for gathering glass, the combination with containing means for a supply of molten glass, of gathering mechanism movable into and out of said containing means and provided with an intake 60 port, a cut-off knife standing normally away from said port across said intake port from side to side, and mechanism for operating the cut-off knife as the gathering device is withdrawn from said containing means 65 which gives the knife its active stroke in

a direction away from the containing means and immediately following said active stroke returns the knife to normal position.

4. In apparatus for gathering glass, the combination with containing means for a 70 supply of molten glass, of gathering mechanism adapted to enter and be withdrawn from said containing means and provided with an intake port, a cut-off knife pivoted to the gathering mechanism and standing 75 normally away from said port, and means operated by the movement of the gathering mechanism as it is withdrawn from said containing means for moving the knife across said intake port from side to side in a direction away from the containing means to make the cut and for immediately returning the knife to normal position.

5. In apparatus for gathering glass, the combination with containing means for a 80 supply of molten glass, of a ram movable into and out of said containing means, a cut-off knife pivoted to the ram, an operating rod connected with said knife, and a fixed cam, a bell crank, one arm of which engages the cam, the operating rod being connected to the other arm, the cam being formed so that the active stroke of the knife is away from the said containing means. 90

6. In apparatus for gathering glass, the combination with containing means for a supply of molten glass, of a ram movable 95 into and out of said containing means, a cut-off knife pivoted to the ram, an operating rod connected with said knife, and a fixed 100 cam, a bell crank, one arm of which engages the cam, the operating rod being connected to the other arm, the cam being formed so that the active stroke of the knife is away from the said containing means, said operating rod comprising two telescoping 105 members and a spring connecting the same together.

7. In apparatus for gathering glass, the combination with containing means for a 110 supply of molten glass, of a ram movable into and out of said containing means, a mold on said ram formed with an intake port on its under side, a knife standing normally away from said intake port, pivoted to the end of the ram, and provided with a blade adapted to be moved across the intake 115 port of the mold from a position on one side of the mold to a position on the other, and mechanism operated by the movements of said ram for causing the knife to pass back and forth across said intake port and return immediately to normal position.

8. In apparatus for gathering glass, the combination with containing means for a 120 supply of molten glass, of a ram movable into and out of said containing means, a mold on said ram formed with an intake port on its under side, a knife pivoted to the end of the ram provided with a blade adapt- 125

- ed to be moved across the intake port of the mold from a position on one side of the mold to a position on the other, and mechanism operated by the movements of said ram for causing the knife to pass back and forth across said intake port, the forward edge of said blade being diagonal with respect to the direction of movement of the blade so as to give the glass a shearing cut. 35
- 10 9. In apparatus for gathering glass, the combination with containing means for a supply of molten glass, of a ram movable in the direction of its length into and out of said containing means, a gathering mold on 40 said ram provided with an intake port, a cut-off device pivoted to the extremity of the ram, and mechanism operated by the movement of the ram away from said containing means for passing said cut-off device across 45 said intake port in the direction away from said containing means, said mechanism being adapted to normally hold said cut-off device in position outwardly of said mold. 50
- 10 10. In apparatus for gathering glass, the combination with containing means for a supply of molten glass, of a ram movable in the direction of its length into and out of said containing means, a gathering mold at 55 the end of said ram provided with an intake port, a cut-off device pivoted to the end of said ram and normally standing outwardly of said gathering mold, and mechanism for causing said knife to pass across said intake port comprising a bell crank pivoted to the 60 ram, an operating rod connecting the bell 35 crank with said cut-off device, an element fixed with reference to the longitudinal movement of said ram formed in one side with a cam slot, and a member on said bell crank which operates in said cam slot. 40
11. In apparatus for gathering glass, the combination with a movable ram, of a gathering mold on the ram, a cut-off device pivoted to the ram, and mechanism for actuating the cut-off device so that in its active 45 stroke it moves in the direction of travel of the ram. 50
12. In apparatus for gathering glass, the combination of reciprocating gathering mechanism provided with an intake port, a cut-off knife standing normally away from 55 said port, and means for moving said knife across said intake port so as to make its cut in the direction of movement of the gathering mechanism. 60
13. In apparatus for gathering glass, the combination of reciprocating gathering mechanism provided with an intake port, a cut-off knife standing normally away from 55 said port, and means for moving said knife across said intake port so as to make its cut in the direction of movement of the gathering mechanism and for immediately returning the knife to said normal position. 65

AUGUST KADOW.

GEOGRE E. DIXON,
L. F. LUSCOMBE.

It is hereby certified that in Letters Patent No. 1,208,791, granted December 19, 1916, upon the application of August Kadow, of Toledo, Ohio, for an improvement in "Cut-Off Mechanism for Glass-Forming Apparatus," errors appear in the printed specification requiring correction as follows: Page 3, lines 49-50, claim 2, and lines 61-62, claim 3, strike out the words "across said intake port from side to side"; same page, line 51, claim 2, and line 63, claim 3, after the word "knife" insert the words *across said intake port from side to side*; and that the said Letters Patent should be read with these corrections therein that the same may conform to the record of the case in the Patent Office.

Signed and sealed this 6th day of February, A. D., 1917.

[SEAL.]

R. F. WHITEHEAD,
Acting Commissioner of Patents.
